CLAIM

The ornamental design for a hand vacuum, as shown and described.

DESCRIPTION

FIG. 1 is a side elevational view of a hand vacuum, formed in accordance with the present invention;

FIG. 2 is a top plan view thereof;

FIG. 3 is a front elevational view thereof;

FIG. 4 is a side elevational view opposite of the view of FIG. 1;

FIG. 5 is a bottom plan view thereof; and

FIG. 6 is a rear elevational view thereof.

The conventional electrical cord has been shown fragmentarily for ease of illustration.

FIG. 2

FIG. 1

FIG. 3
